UNITED STATES PATENT OFFICE

156,575

TELEVISION CABINET

**Leland George Stone, Fort Wayne, Ind., assignor
to The Magnavox Company, Fort Wayne, Ind.,
a corporation of Delaware**

Application October 4, 1948, Serial No. 148,952

Term of patent 7 years

(Cl. D56—4)

To all whom it may concern:

Be it known that I, Leland George Stone, a citizen of the United States, residing at Fort Wayne, in the county of Allen and State of Indiana, have invented a new, original, and ornamental Design for a Television Cabinet, of which the following is a specification, reference being had to the accompanying drawings, forming a part thereof.

In the drawings:

Fig. 1 is a front perspective view of my television cabinet with the tuning panel door in open position;

Fig. 2 is a front perspective view of my television cabinet with the tuning panel door closed;

Fig. 3 is a plan view of the cabinet with the tuning panel door in open position; and

Fig. 4 is a side elevational view thereof with

a portion of the view in section through the tuning panel and door.

The characteristic features of my design reside in the portions shown by means of full lines in the drawing.

I claim:

The ornamental design for a television cabinet, substantially as shown and described.

LELAND GEORGE STONE.
